C. H. THORDARSON

VERNIER RHEOSTAT

Filed May 22, 1922

UNITED STATES PATENT OFFICE.

CHESTER H. THORDARSON, OF CHICAGO, ILLINOIS.

VERNIER RHEOSTAT.

Application filed May 22, 1922. Serial No. 562,607.

This invention relates to improvements in rheostats for regulating or adjusting an electrical circuit, and refers more particularly to a novel vernier rheostat, the circuit of which 5 comprises a main winding, constituting almost the entire rheostat circuit, and a short or fractional part comprising, in length, a short subdivision of said entire circuit and which is in circuit with said winding and binding posts for connection to an external circuit, and containing also a main sliding element which travels over and in contact with the main winding or its contacts and a secondary sliding element which 10 travels independently of the main sliding element over the fractional circuit part, whereby the latter element or member is capable of cutting in or out fractional portions between one or more coils or contacts 15 of the main winding, so as to thereby attain very minute subdivisions of the rheostat circuit.

An object of the invention is to provide an exceedingly simple and efficient rheostat of 20 this character, in which the parts may be economically made and economically assembled, and also to provide a construction in which the fractional portion of the circuit is well insulated from the main winding of 25 the rheostat circuit.

A further object of the invention is to produce a construction of rheostat in which the operative parts are compactly arranged and protected by the general construction of 30 the device from exterior bruises.

The construction herein shown is particularly well adapted for use in the tuning circuits of radio transmitting and receiving sets but may be adapted to other uses where 35 fine graduations of current flow through a circuit is required.

The invention consists in the combination and arrangement of the parts shown in the drawings and described in the specification, 40 and is pointed out in the appended claims.

In the drawings:

Figure 1 is an end view of a rheostat embodying my invention.

Figure 2 is an axial section thereof, with 45 parts shown in elevation.

Figure 3 is a diagram of the rheostat circuit.

Figure 4 is a modified diagram of the rheostat circuit.

Referring first to Figure 3, 10 designates 50 a winding constituting the principal part of

the rheostat circuit. 11 designates a fractional part of said circuit which, in practice, is made of a length of approximately that of one or two of the coils of the winding. 12 55 designates a conducting arm which is adapted to travel along the length of and in contact with the winding 10, and 13 designates a like conducting arm which is adapted to travel along and in contact with the fractional circuit part. Said arms are shown in Figure 4 electrically connected, as at the point 14. 15, 16 designate binding posts by which the rheostat circuit is connected to the wires of an external circuit. The said 60 arms 12, 13 are, in the mechanical construction, mounted to rotate on the same axis, and each of said arms is adapted to be independently movable so that, with the arm 12 on one of the coils or contacts of the 65 winding, the other arm 13 can be moved along the fractional circuit part 11, so as to divide the current force into as many increments as the length of said fractional conductor bears ratio to the length of the 70 coil or coils with which the arm 12 is in contact.

Referring now to the illustrated mechanical construction constituting one embodiment of my invention, 17 designates a metal 75 base plate. It is provided with a rim 18 which is made of one piece of metal that is curved to form an almost complete circular element that may be fixed to the plate 17, as by means of an integral spur or flange 20 80 struck up from said base plate and riveted to the ends of the rim member. The said rim is shown as made of thin gauge metal and is of a width to form a protecting wall 85 for parts enclosed therein, as will herein- 90 after be described.

The said rim also forms a core or support for the winding 10 of the rheostat circuit, said winding being wound in elongated coils about the said rim throughout the principal portion of its circumferential length. 100 The winding is insulated from the metal of the rim by an insulating tube 21 made to fit closely about the portions of the rim at the sides of the flange or spur 20 and directly supports the winding 10.

22 designates a disc made of insulating material which is seated on the base 17 and is enclosed by the rim 18 and its winding 10. Said insulating disc 22 at its base is 110 made the full diameter of the rim, and is formed at said base with a radial extension

or flange 24 that extends beneath the winding 10 to insulate the winding from the base 17. The disc 22 is provided near its edge remote from the flange 24 with an external 5 annular groove 25 in which is seated the fractional portion 11 of the rheostat circuit, said fractional circuit part being a plain curved wire. Said fractional circuit portion is connected at one end to the binding 10 post 15 and is laid between its ends in said external groove 25 and is open at its other end. The coil 12 is connected at one end with the binding post 16 and is open at its other end, the fractional circuit part and 15 winding being thus in series through the arms 12 and 13. Said disc 22 is provided exterior to said groove 25 with an annular recess or groove 26 of some depth, and the latter groove is flanked by an annular 20 closing flange 27 of less height than the thickness of said disc.

28 designates a hollow operating shaft which extends through a mounting board B, in which the shaft is rotatively mounted. Said shaft is reduced at its inner end and is rotatively mounted in a sleeve 28' which extends through the base plate. Said shaft extends beyond the disc 22 and carries at its outer end the angularly adjustable conducting arm 13 which extends radially from the shaft. Said arm 13 is provided at its free end with a down-turned contact finger 30 for engagement with the fractional circuit part 11. Said contact finger 30 also travels in the groove 26 to hold it engaged with the fractional circuit part 11 and also to prevent contact of said down-turned finger with the winding 10. Said hollow shaft is provided with a hand wheel 31 by which to rotate it and the conducting arm 13.

32 designates a second shaft which extends through and is mounted to rotate in the shaft 28. Said second shaft extends 45 outwardly beyond the hollow shaft 28 and is provided beyond the hand wheel 31 of the shaft 28 with an independently actuable hand wheel 33. The shaft 32 also extends at its inner end beyond the shaft 28 and carries at its inner end the contact arm 12 which is disposed radially to the shaft and is adapted for contact at its outer end with the coils of the winding 10.

As herein shown, the conducting arm 13 is fixed to a reduced, threaded portion of the shaft 28 by being provided with an enlarged perforated head for the passage of said reduced end, and the said head is clamped between a solid washer 34 and a 55 nut 35 threaded to said shaft. The washer 34 is forced by the nut 35 against a split or spring washer 36, which latter yieldingly bears on the inner end of a flanged sleeve 28', which surrounds the shaft 28 at the 60 disc and constitutes a bearing sleeve for the 65

latter shaft. The said conducting arm 12 is likewise provided with a perforated head through which the threaded, reduced, inner end of the shaft 32 extends, and said arm is held fixedly on said shaft between lower and upper nuts 38, 39. The metal to metal contact of the mounting of the conducting arms 12 and 13 and their fastening nuts and washer constitutes an electrical connection between said arms, which is indicated in the 70 diagrammatic view of Figure 3 by 14.

With the construction described, it will be observed that the wiping contact arms are capable of being rotated each independently of the other by reason of the independent bearing of the shaft 32 in the hollow shaft 28. Thus, with the outer end of the conducting arm 12 in contact with one or more of the coils of the winding 10, the conducting arm 13 can be angularly adjusted on the 80 fractional circuit part 11, so as to further subdivide the current passing through the rheostat, due to the length of said fractional circuit part relatively to the length of the coil or coils of the winding with which the 90 conducting arm 12 is in closed circuit.

The said base plate 17 may be attached to the inner face of a mounting board B which, in practice, may be a wall of a cabinet or like structure in which the electrical apparatus to be regulated by the rheostat is contained. The fastening of the plate 17 may be effected by means of screws 22' extending through said plate and the conducting disc into said wall. The hand piece 31 of the outer or tubular shaft 28 is spaced from said mounting board a distance to permit it to be readily grasped to turn the same and the conducting arm actuated thereby, and the hand piece of the shaft 32 is spaced from the hand piece 31 to afford free access thereto without disturbing the latter hand piece.

An advantage of the construction shown is that the winding 10 and the fractional portion 11 of the circuit are arranged concentrically with respect to each other, so that the conducting arms may be made to rotate on axes that are concentric to said winding and fractional circuit part of the rheostat circuit. This contributes to the compactness of the device. Furthermore, the arrangement shown is such that the conducting arms are enclosed by the rim which carries the winding 10 so that said parts are 110 protected.

The conducting elements of the rheostat, embracing the winding 10, the fractional circuit part 11, the wiping conducting arms 12 and 13 and their mounting, as well also as the insulating disc 22, and the rim 18, are made of materials which are not affected by heat developed in the circuit conductors, so that thereby, after the parts have been 115 assembled and adjusted, the accuracy of the 120 125 130 135

device is assured. A stop 40 is mounted on said rim at one end of the winding 10 to prevent contact of the conducting arm 12 with one of the binding posts. A like 5 stop may be provided on the disc to limit angular movement of the other conducting arm 13.

In Figure 4 is shown a modified wiring diagram, wherein the winding 10' and short 10 circuit part 11 are in direct series and connected to binding posts 15', 16', and wherein the arms 12', 13' are not directly in series with the coils and circuit part and are represented as electrically connected by the 15 wire 14'.

I claim as my invention:

A vernier rheostat comprising a base, a rim outstanding therefrom and fixed thereto, an insulating body within said rim,

formed on its circumference with a groove 20 and radially beyond said groove with a guard flange, a conductor embracing a winding on and insulated from said rim, and a fractional circuit part fitted in said body groove, and electrically connected conducting arms mounted for separate angular adjustment about an axis concentric to said rim, adapted for wiping contact, one with said winding, and the other provided with an inturned finger lying outside said body 25 periphery for wiping contact with said fractional circuit part, and lying within said guard flange.

In witness whereof I claim the foregoing as my invention, I hereunto append my signature this 17 day of May, 1922. 35

CHESTER H. THORDARSON.
